CLAIM

The ornamental design for an arbor for cutting blades, as shown and described.

DESCRIPTION

FIG. 1 is a top, right perspective view of an arbor for cutting blades of the present invention;

FIG. 2 is a top, left perspective view of the arbor for cutting blades of FIG. 1;

FIG. 3 is a first side elevation view of the arbor for cutting blades of FIG. 1;

FIG. 4 is a second side elevation view of the arbor for cutting blades of FIG. 1; and,

FIG. 5 is a top plan view of a cutting blade with the arbor for cutting blades of FIG. 1.
